UNITED STATES PATENT OFFICE.

WILLIAM G. PRICE, OF NEW CASTLE, PENNSYLVANIA.

BRAKE-RIGGING.

1,070,913.

Specification of Letters Patent.

Patented Aug. 19, 1913.

Original application filed November 25, 1911, Serial No. 662,458. Divided and this application filed May 1, 1913. Serial No. 764,902.

To all whom it may concern:

Be it known that I, WILLIAM G. PRICE, a citizen of the United States, and resident of New Castle, in the county of Lawrence and State of Pennsylvania, have invented a new and useful Improvement in Brake-Rigging; and I do hereby declare the following to be a full, clear, and exact description thereof.

My invention relates to brake-hangers.

10 The present invention is a division of an application filed by me Nov. 25, 1911, Serial No. 662,458.

It comprises, generally stated, a suitable bracket or support, a brake-hanger suspended therefrom, a brake-shoe head secured to one side of said hanger, and means intermediate the upper and lower end of said hanger engaged by said hanger to prevent lateral movement of same.

20 Referring to the drawing, Figure 1 is a side elevation of a portion of the truck showing my invention applied thereto; Fig. 2 is a cross-section on the line 2—2 Fig. 1; and Fig. 3 is a modified form of my invention.

25 In the accompanying drawing, the numeral 2 designates a suitable truck-frame supported on the wheels 3, the springs, journal-box, &c., being of any suitable construction. The truck-frame is further provided with the equalizer-bars 4 which extend from one journal-box to the other. A bracket 5 is secured by bolts 6 to the side frame 2 of the truck, said bracket having the conical projection 7 which enters a conical seat 8 in the hanger 9. A bolt 10 passes through the hanger bracket and side frame to secure the hanger to the bracket and a spring 11 is interposed between the side frame and the 35 nut 12. The bracket 5 has the downwardly extending arm 13 which is adapted to enter the recess 14 formed between the hanger 9 and the off-set 15 on said hanger.

30 The lower end of the hanger 9 has the projection 16 which enters the recess 17 in the brake-shoe head 18. A bolt 19 connects the hanger with the brake-shoe head, and a spring 20 on said bolt is interposed between said hanger and the nut 21.

50 The live-lever is indicated by the reference numeral 22 and the brake-rod 23 is connected to the upper end of said live-lever. The live-lever is connected to the lugs 24 on the brake-shoe head and the lower

end of the lever is connected to the ordinary 55 turn-buckle 25. By the engagement of the arm 13 of the bracket 5 with the recess 14 of the hanger, the lateral movement of the hanger is prevented and the shoe is held in proper alinement with the wheel. In this 60 case the guiding means for holding the hanger against lateral movement is located above the connection of the hanger with the brake-shoe head, and the guiding arm 13 prevents any undue lateral movement of the 65 hanger. The hanger is supported by the truck frame instead of by the equalizer-bar, as in my former application.

In Fig. 3 I have illustrated a modified form of my invention in which the bracket 70 26 is carried supported by the equalizer-bars 4 and said bracket has the downwardly projecting arm 27 which engages the recess 14 in the hanger 9.

What I claim is:

75 1. In brake-rigging, the combination of a suitable support, a single brake-hanger suspended therefrom, a brake-head, said hanger being connected to one side of said brake-head, and means intermediate the upper and lower ends of said hanger engaged by said hanger to prevent lateral movement of same.

2. In brake-rigging, the combination of a suitable support, a single brake-hanger pivotally supported thereby, a brake-head, 85 said brake-hanger being connected to one side of said brake-head, and guiding means on said support slidably engaging said hanger at a point intermediate the upper and lower ends of said hanger.

90 3. In brake-rigging, the combination of a suitable support, a brake-hanger suspended therefrom, a brake-head, and guiding means on said support slidably engaging said hanger at a point intermediate the upper and lower ends of said hanger.

95 4. In brake-rigging, the combination of a suitable support, a brake-hanger suspended therefrom, a brake-head, and means engaged by a portion of said hanger intermediate its ends to prevent the lateral movement of same.

100 5. In brake-rigging, the combination of a suitable support, a brake-hanger suspended therefrom, a brake-head, and a guide engaged by a portion of said hanger intermediate of its ends to prevent lateral movement of same.

6. In brake-rigging, the combination of a suitable support, a brake-hanger suspended therefrom, a brake-head, and a bracket on said support having a guide-arm engaging 5 a seat on said hanger.
7. In brake-rigging, the combination of a suitable support, a brake-hanger suspended therefrom, a brake-shoe head, and a downwardly extending arm on said support 10 engaging a seat on said hanger.
8. In brake-rigging, the combination of a suitable support, a brake-hanger suspended therefrom, a brake-shoe head, a bracket on said support, and a guide-arm on said 15 bracket engaging a seat on said hanger intermediate its ends.
9. In brake-rigging, the combination of a truck side-frame, a bracket carried by said side-frame, a hanger suspended from said bracket, and a downwardly projecting 20 guide-arm on said bracket engaging a seat on said hanger.

In testimony whereof I the said WILLIAM G. PRICE have hereunto set my hand.

WILLIAM G. PRICE.
